UNITED STATES PATENT OFFICE.

LEVI H. PAGE, OF CHICAGO, ILLINOIS, ASSIGNOR TO THE GARDEN CITY FILLER COMPANY, OF SAME PLACE.

EGG-CARRIER.

SPECIFICATION forming part of Letters Patent No. 445,074, dated January 20, 1891.

Application filed March 3, 1890. Serial No. 342,333. (No model.)

To all whom it may concern:

Be it known that I, LEVI H. PAGE, a citizen of the United States, residing at Chicago, in the county of Cook and State of Illinois, have 5 invented certain new and useful Improvements in Carriers for Eggs, Fruit, &c., of which the following is a full, clear, and exact description, reference being had to the accompanying drawings, and to the letters of reference marked thereon, which form part of this 10 specification.

My present invention relates to improvements in the construction of carriers for the packing or transportation of eggs, fruit, &c., 15 wherein slats or strips of wood or other suitable material are operatively arranged to form subdivisions or series of separate compartments for the reception individually of the articles to be packed or transported, the invention consisting in certain improvements 20 in the slat or strip interlocking devices whereby the construction is securely held together, the durability of the same is enhanced, and the form primarily given thereto is maintained, 25 together with a certain other improvement in construction which enables the folding of the carrier into compact shape for storage or shipment to better advantage and with greater safety to the construction than is ordinarily 30 the case with carriers of similar class.

The objects of the invention are attained by the means shown in the accompanying drawings, in which—

Figure 1 is an enlarged broken detail in perspective mainly intended to illustrate the form and operative arrangement of the interlocking devices. Fig. 2 is a view in perspective of a complete carrier embodying my several improvements, the view being in part broken 35 away for the purpose of showing the interior of the carrier and the intersecting arrangement of the slats or strips to form the subdivisions. Fig. 3 is a plan view intended to illustrate the advantage attained by the employment of my said improvements which relate to the folding of the carrier for storage or shipment.

Referring to the details of construction and arrangement shown in the several above-described views, A indicates the strips which 45 form the outer portion or frame of the carrier,

B strips disposed in one direction athwart the space formed by said strips A, and B' narrower strips located transverse said space and intersecting, in the manner hereinafter set 55 forth, the said strips B.

The strips A are provided transverse their length with slots a^2 a^3 and a tongue a , the free end of which is arranged to project to a point desirably in alignment with the lower portion 60 of the slots a^3 , which is desirably in alignment with the upper portion of the slot a^2 , the disposition of the several slots forming, laterally of the slot a^2 , shoulders a' . (Fully shown in Fig. 1.)

The strips B are provided at proper distances in their length with transverse slots b' , of dimensions suitable for the passage therethrough of the transverse strips B', and at their ends with one or more tongues b^2 , proportioned 70 to pass through the openings formed in the strip A by the slots a^3 and by the deflection outwardly of the tongue a . The said tongues b' are provided in their lateral margins with notches b , of depth substantially in correspondence with the width of the respective slots a^3 , the distance transverse the said tongues intermediate the notches b substantially corresponding with the length of the slots a^2 .

The manner of interlocking the strips to form the carrier-frame is as follows: The tongues b^2 being carried against the tongues a deflect the same outwardly, passing thereunder and through the slots a^3 until the 85 notches b allow the said tongues b^2 to drop into proper position within the slots a^2 , the notches b or the shoulders formed thereby embracing the shoulders a^2 and locking the strips together in one direction, while the 90 tongues a secure the tongues b^2 within the slots a^2 in the other direction. The shoulders formed in the tongues b^2 by the notches b being operatively contiguous to the strip A, aside from the interlocking purpose which 95 they subserve, are of great utility in the matter of preventing the material of which the strips are composed from warping out of proper form and therefore in the preservation of the integrity of the construction.

It will be noted that in egg and fruit carrier constructions of the class to which my im-

provements relate the connecting of the strips has been maintained to the extent of interlocking the ends of the outside strips, which not only prevents the folding of the carrier into perfect compact form, but under ordinary usage causes the ends of the strips, if at all weakened by the presence of interlocking devices, to be broken and therefore rendered unfit or objectionable for use. To obviate such difficulties the strips A of my construction are interlocked with the strips B B' and not with each other, thus leaving their terminals c free to occupy positions, as shown in Fig. 3, without the possibility of unduly straining or damaging the same when folded for transportation, &c.

Having thus described my invention, I claim as new and desire to secure by Letters Patent—

- 20 1. In carriers for fruit, eggs, &c., of the class herein described, the combination, with the outside longitudinal and transverse strips having their edges adjacent to but not interlocked with each other, said strips being formed with slots a^2 a^3 and tongues a, of the notched compartment-forming strips adapted to interlock with said outside strips.
- 25

2. In carriers for eggs, fruit, &c., wherein slats or strips are employed to form series of separate compartments, substantially as herein set forth, the frame-work composed of the outside and compartment-forming strips, said outside strips being interlocked or otherwise connected with the compartment-forming strips and not connected or interlocked with each other, all arranged substantially in the manner and for the purpose herein described.

3. In carriers for fruit, eggs, &c., of the class herein described, the longitudinal and transverse outside strips, said longitudinal strips being unconnected with said transverse strips, in combination with longitudinal and transverse compartment-forming strips, the ends of said longitudinal compartment-forming strips being secured to said transverse outside strips and the ends of said transverse compartment-forming strips being secured to said longitudinal outside strips.
